UNITED STATES PATENT OFFICE.

GEORGE CURTIS WRIGHT, OF WORCESTER, MASSACHUSETTS, ASSIGNOR TO WILLIAM JAMES HOGG, OF SAME PLACE.

DESIGN FOR A CARPET.

SPECIFICATION forming part of Design No. 14,600, dated January 29, 1881.

Application filed December 14, 1883. Term of patent 3½ years.

To all whom it may concern:

Be it known that I, GEORGE CURTIS WRIGHT,
of the city of Worcester, county of Worcester,
State of Massachusetts, have invented and produced a new and original Design for Carpets,
of which the following is a specification.
The nature of my design is fully represented in the accompanying photographic illustration, to which reference is made.

I claim as my invention—

The design for a carpet, as shown.

Witnesses: GEORGE CURTIS WRIGHT.
